ATTORNEY

UNITED STATES PATENT OFFICE.

HORRIS W. TODD, OF DRUMRIGHT, OKLAHOMA.

ROD SOCKET.

1,419,780.

Specification of Letters Patent. Patented June 13, 1922.

Application filed March 29, 1921. Serial No. 456,524.

To all whom it may concern:

Be it known that I, HORRIS W. TODD, a citizen of the United States, residing at Drumright, in the county of Creek and State 5 of Oklahoma, have invented new and useful Improvements in Rod Sockets, of which the following is a specification.

This invention relates to oil well devices and has for its object the provision of a 10 novel socket for use in connection with sucker rods, the socket being formed of relatively longitudinally movable interengaging sections or sleeves normally held in association but capable of movement out of 15 gaging position for subsequent springing to effect disengagement of the rod therefrom.

An important object is the provision of a device of this character which will have 20 strength as its main feature, the socket having greater thickness than ordinary sockets and having such a positive interlocking action of its sections as to positively prevent accidental springing or other separation 25 which might cause dropping of the sucker rod.

An additional object is the provision of a device of this character which will be simple and inexpensive in manufacture, 30 highly efficient in use, durable in service, and a general improvement in the art.

With the above and other objects and advantages in view, the invention consists in the details of construction to be hereinafter 35 more fully described and claimed and illustrated in the accompanying drawings in which—

Figure 1 is a side elevation of my socket with the parts in initial or disengaged position,

Figure 2 is a similar view showing the sections engaged,

Figure 3 is a longitudinal sectional view showing the sucker rod in position,

Figure 4 is a cross sectional view taken through the slip joint,

Figure 5 is an enlarged perspective view of the portions of the joint disengaged,

Figure 6 is a longitudinal sectional view 50 showing auxiliary slips.

Referring more particularly to the drawings, the letter A designates a well casing or tubing and B designates a sucker rod.

My socket comprises a rigid cylindrical upper portion 10 having an angular portion 55 11 for engagement by a wrench to effect rotation and carrying at its upper end a threaded extension 12 screwed into a correspondingly threaded socket 13 in an extension 14 of the same formation as the member 10. 60 Each of these members, that is 10 and 14, is formed with a transverse hole 15 within which is disposed a spring-pressed pin 16 having a beveled outer end 17 and held in place by a screw 18 which closes the end of 65 the hole opposite that through which the pin extends. Rigidly secured to the upper portion 10 is a substantially semi-cylindrical body or split tube 19 which has its lower end formed with lateral extensions 20 70 formed at their upper edges with undercut shoulders 21. Secured within the lower end of this body is a substantially semi-circular seat 22 having a beveled lower edge 23 and secured above this seat is a slip 24 which is 75 arcuate in form and which has a beveled upper edge 25.

Designed for co-operation with the above described parts, is a substantially semi-cylindrical body 26 which, together with the 80 body 19 forms a cylindrical tube and at its upper end this body 26 is formed with a suitable sleeve 27 adapted for engagement over and about the member 10 and designed to have its lower edge engaged against the upper edge of the body 19. At its lower end the body 26 is cut away, as shown at 28, and at such cut-away portion is formed with undercut shoulders 29 designed to conformingly engage with the shoulders 21. Secured 85 within the lower end of this body 26 is a seat 30 complementary to the seat 22 and having a similarly beveled lower end 31. Disposed above the seat 30 is a slip 32 which 90 has its lower end resting upon the upper end of the seat 30 and which is hingedly mounted by means of rivets 33 which pass through the wall of the member 26 and which are secured to a small plate 34 fitting loosely within a recess 35 in the wall of the member 26. 100 The outer face of this slip and the inner surface of the wall of the member 26 are recessed as indicated at 36 for the retention of a coiled spring 37 which normally urges the slip inwardly.

In the assembling of the parts, the sucker

rod B is disposed within the semi-cylindrical body 19, or rather the body is engaged over the sucker rod. The body 26 is then associated with the body 19 with its sleeve portion 27 slidably engaging over the member 10. The body 26 is then slid downwardly until the shoulders 29 thereon engage the shoulder 21 at which time the slips 24 and 32 will be complementary to each other and 10 will form an inwardly extending flange adapted to be engaged by the enlargement C on the sucker rod. When the parts are moved into this position the sleeve 27 will slide over the lowermost pin 16, the pin automatically retracting owing to the fact that 15 its outer end is beveled as shown at 17. When the shoulders 21 and 29 are in conforming engagement the sleeve 27 will have passed downwardly beyond the lowermost 20 pin 16 whereupon the pin will spring outwardly and engage over the upper edge of the sleeve 27 and prevent upward longitudinal movement of the body 26, with respect to the body 19. Initially this pin holds the 25 lower edge of the sleeve 27 for preventing downward movement of the sleeve and body 26 until such movement is desired. The provision of the spring 37 is an important feature as it urges the slip inwardly so that 30 it will have a sort of ratchet action to prevent the sucker rod from being pulled downwardly while permitting it to be slid freely upwardly with respect to the body 26 and member 19.

35 In Figure 6 I have shown an auxiliary sleeve 35 designed to constrict the bore of the mating substantially semi-cylindrical members in case there is a break in the sucker rod at its smaller portion.

40 From the foregoing description and a study of the drawings it will be apparent that I have thus provided a simply constructed and easily assembled socket device which will be of manifest utility and advantage 45 and which may be very quickly and easily associated with a sucker rod.

While I have shown and described the preferred embodiment of my invention, it is of course to be understood that I reserve 50 the right to make such changes in the form, construction, and arrangement of parts as will not depart from the spirit of the invention or the scope of the subjoined claims.

Having thus described my invention, I 55 claim:

1. In combination with a well tubing and sucker rod, a socket device comprising an upper member supported from the top of the well, a substantially semi-cylindrical hollow body secured thereto and having its lower end formed with circumferential extensions 60 formed at their upper edges with undercut shoulders, a second substantially semi-cylindrical hollow body associated with said 65 first named body and having its upper end

formed as a sleeve slidably engageable over said upper member and having its lower end cut away circumferentially and formed with undercut shoulders conformingly engaging said first named shoulders, and mating inwardly extending projections at the lower ends of said sections, said assembled bodies being designed to receive the sucker rod, the latter having an enlargement engageable with said retaining means. 70 75

2. In combination with a sucker rod having an enlargement, a socket device comprising a solid upper member adapted for connection with other members disposed thereabove within a well, a depending substantially semi-cylindrical hollow body secured to said upper member and having its lower end circumferentially prolonged and formed with undercut shoulders, a second substantially semi-cylindrical hollow body having 80 its upper end formed as a sleeve slidably engageable about said upper member and having its lower end cut away circumferentially and formed with undercut shoulders conformingly engaging said first named shoulders, seats within the lower ends of the body 85 matingly cooperating, and slips secured within said lower ends of the bodies immediately above said seats. 90 95

3. In combination with a sucker rod having an enlargement, a socket device comprising a solid upper member adapted for connection with other members disposed thereabove within the well, a depending substantially semi-cylindrical hollow body secured 100 to said upper member and having its lower end circumferentially prolonged and formed with undercut shoulders, a second substantially semi-cylindrical hollow body having 105 its upper end formed as a sleeve slidably engageable about said upper member and having its lower end cut away circumferentially and formed with undercut shoulders conformingly engaging said first named shoulders, seats within the lower ends of the body 110 matingly cooperating, and slips secured within said lower ends of the bodies immediately above said seats, the upper edges of 115 said slips being outwardly and downwardly beveled, one slip being hingedly mounted and spring pressed toward the other.

4. In combination with a sucker rod having an enlargement, a socket device comprising a solid upper member adapted for connection with other members disposed thereabove within a well, a depending substantially semi-cylindrical hollow body secured to 120 said upper member and having its lower end circumferentially prolonged and formed with undercut shoulders, a second substantially 125 semi-cylindrical hollow body having its upper end formed as a sleeve slidably engageable about said upper member and having its lower end cut away circumferentially and formed with undercut shoulders conform- 130

ingly engaging said first named shoulders, seats within the lower ends of the body matingly cooperating, slips secured within said lower ends of the bodies immediately above 5 said seats, and a transverse normally projecting spring-pressed pin within said upper member and engageable with the lower edge

of the sleeve to hold said second named body elevated or engageable with the upper end of the sleeve whereby to hold said bodies 10 against relative longitudinal movement with said shoulders engaged.

In testimony whereof I affix my signature,
HORRIS W. TODD.
